UNITED STATES PATENT OFFICE

JOHN A. WHERRY, OF NEW ORLEANS, LOUISIANA

COLLATING DEVICE FOR TYPE-WRITERS.

1,320,593.

Specification of Letters Patent.

Patented Nov. 4, 1919.

Application filed January 31, 1918. Serial No. 274,199.

To all whom it may concern:

Be it known that I, JOHN A. WHERRY, a citizen of the United States, residing at New Orleans, in the parish of Orleans and 5 State of Louisiana, have invented certain new and useful Improvements in Collating Devices for Type-Writers; and I do hereby declare the following to be a full, clear, and exact description of the invention, such as 10 will enable others skilled in the art to which it appertains to make and use the same.

This invention relates to a collating device for typewriters, and the primary object of the invention resides in the provision of a 15 collating device on which the work sheets may be assembled or collated and carried to the printing position on the typewriter without disarrangement. The device forming the subject matter of this application is in 20 the nature of an improvement on the device which is described and claimed in my pending application, Serial No. 258,148, filed October 15, 1918.

In the drawings:

25 Figure 1 is a front elevation of an embodiment of my device, showing the same in place on a portion of a typewriter frame;

Fig. 2 is a perspective view of the device;

Fig. 3 is a rear elevation thereof;

30 Fig. 4 is a side elevation;

Fig. 5 is a vertical sectional view;

Fig. 6 is a fragmental perspective view of one form of the sheet alining strip;

Fig. 7 is an elevational view of a modified 35 form of the alining strip;

Fig. 8 is a transverse sectional view of the device shown in Fig. 7.

Mounted on the forward side of the carriage frame 1 is a pair of upwardly extending standards 2, which are secured to the frame by suitable fasteners 3. At the rear of the carriage frame a pair of relatively longer standards 4 are located, which standards are secured to the frame by suitable fasteners 5. The collating board 6 is attached to a frame which includes side bars 7, by suitable brackets 8. A pair of links 9 are pivoted at 10 to the front standards 2 and extend to and are pivotally attached to a rod 11 which extends between the side bars 7 of the collating board frame. From the upper ends of the rear standards 4 links 12 extend. These links are pivoted to the standards 4 at 13 and to a rod 14 which extends between 55 the side bars 7. With this arrangement of links the collating board may be swung into

a vertical position, such as illustrated in Figs. 4 and 5, for instance, or on the other hand, it may be raised and swung into an inclined position, such as illustrated in Fig. 2, the links 9 and 12 moving pivotally during the swinging of the board from one of said positions to the other. The movement of the links 12 and consequently of the collating board, may be limited by the insertion 60 of a pin in any of the series of holes 7' in the side bar 7 of the frame.

A pair of helical springs 15 surround the rod 13, and each of these springs is attached at one of its ends to the adjacent standards 4 70 by a suitable arm 16. At the other end the spring is attached to a clutch member 17, which is adapted to co-operate with a similar clutch member 18, so that the tension of the spring may be varied at the will of the operator. A similar pair of springs 19 are mounted on the rod 10. These springs are provided with adjustable clutches 20 similar to those already described, and are attached at 21 through arms 22 to the carriage frame. 80 These springs 15 and 19 tend to raise the collating board so as to move the same from the position shown in Fig. 5, to the position shown in Fig. 2, or at least to assist in such movement. The degree of assistance is, of course, determined by the tension which is placed upon the springs through the adjustment of the clutches associated therewith. The effect of the springs is normally overcome and the collating board maintained in 90 its vertical position by a latch member 23, which is pivoted on a rod 24 extending between the side bars 7 of the frame. This rod 24 is provided at its ends with operating handles 25 and the latch member 23 is normally maintained in engagement with a notch 26 in the adjacent link 12 by a spring 27 which encircles the rod 24, is attached thereto and is at its other end attached to the rod 14. Upon the disengagement of the 95 latch member 23 from the notch 26, however, the springs 15 and 19 will act to raise the collating board.

The collating board frame is supported on the usual inner carriage ends 90. 105 The platen 28 is rotatably supported on the usual shaft 29 that extends through the inner carriage ends. The ends of shaft 28 support the activating ratchet 29 and the operating knobs 30. The attachment of the 110 collating board to the inner carriage ends is such that the inner carriage and platen of

the typewriting machine will be swung simultaneously with the collating board. When the collating board is swung into its vertical position, the inner carriage, platen and actuating mechanism will assume operative relation with the typewriter carriage, and the extended lugs on inner carriage ends will rest within the inner carriage lift hooks 31 which are made stationary with the carriage frame by suitable fasteners 32.

A pair of arms 33 are pivoted at 34 to the side bars 7 of the collating board frame and extend rearwardly therefrom. A sheet shelf 35 is pivotally supported at 36 on these arms and extends downwardly and around the platen as at 37. The lower end of this sheet shelf 35 is supported by a rod 38, which extends through keepers 39 on the shelf, the keepers being elongated so as to permit the movement of the shelf to and away from the platen. The lateral movement of this shelf on the rod 38 is prevented by collars 40, which are secured to the rod 38. This sheet shelf 35 is provided with a series of feed rollers 41 similar to those described and illustrated in my co-pending application above referred to, and the rollers are held normally in contact with the face of the platen by resilient means 42, which in one phase take the form illustrated in Fig. 5. These springs 42 are secured to rod 43 near side bars 7 and to the sheet shelf 35 by adjustable screws 44, the screws being provided so that the tension of the springs may be varied at the will of the operator. However, the effect of these springs 42 may be overcome and the sheet shelf moved away from the platen to permit the insertion of the sheet therebetween by means of cams 45, which are mounted on a rod 46, the rod extending between and being pivotally mounted in the side bars 7. These cams 45 operate in the notches 47 in the arms 33, and are actuated by means of handles 48 located at the sides of the collating board and secured to the rod 46. When the handles are turned downwardly the cams 45 are actuated so as to depress the arms 33 and consequently move the sheet shelf away from the platen against the tension of the springs 42. In another phase, the resilient means takes the form illustrated in Fig. 8, wherein a spring 49 encircles the rod 34, is secured thereto by a suitable clutch 50, which is provided to vary the tension of the spring and is associated with the rod 46 through the medium of a yoke 51. When this form of resilient means is used, the springs 42 may be dispensed with, but it is to be understood that the spring 49 may be used in conjunction with the springs 42.

A plurality of brackets 52 are mounted on the collating board and are adjustable transversely thereof in slots 53, the brackets

being held in their adjusted positions by suitable thumb screws 54. Sheet alining strips or side gages 54 are mounted loosely on these brackets 52 by means of screws 55, which extend through diagonally arranged slots 56 in the vertical webs of the angular gages. These sheet alining strips or gages 54 are thus free to move to and away from the collating board 6 in an acute angular direction, the movement being toward the platen, and they are held normally in contact with the surface of the collating board by their weight. Furthermore, they are provided with scales indicated generally by the reference character 56' which assist in the positioning of the sheets and are also provided with resilient clips 57 for the purpose of holding the ledger and statement sheets in place during the arrangement of the same on the board. Each of these clips 57 is provided with a mark 58 which coincides with a corresponding mark on the sheet alining strips or gages. The lowermost of the brackets 52 are each provided with an extending arm 59, which terminates in a finger 60, and is provided with a roller 61. The finger and roller extend over the platen and the roller normally bears against the same, being held in such position by the resiliency of the arm 59.

Furthermore, the board itself is provided with transversely extending lines 62 and lines 63 which extend perpendicular to the lines 62. The lines 62 coincide with the graduations on the gages 54. Extending parallel to the axis of the platen 27 is a scale 64 on which the designations indicate the printing positions of the typewriter machine and the platen itself is provided with circumferential lines 65, as well as with lines 66, which are arranged parallel to its axis, which will assist in determining the proper positions of the sheets to be collated.

In another form of the invention, such as illustrated in Fig. 6 of the drawing, I provide in addition to the clips 57, additional clips 67 which are secured to the vertical webs of the gages 54 by thumb screws, which screws are adjustable in longitudinally extending slots 69. The clips 67 are provided with notches 69', which are adapted to coincide with the corresponding lines on the gages.

In the modified form of the invention the sheet alining strips or gages are somewhat modified. This modified form is disclosed in Figs. 7 and 8, and includes parallel strips 70, which are adjustable to and away from each other, or transversely across the collating board, and are adapted to be held in their adjusted positions by thumb screws 71. Second strips 72 are mounted on the outer faces of the strips 70 and are provided with slots 73 extending longitudinally thereof. Each of these strips 72 has superimposed

thereon a scale 74 having graduations corresponding to the transverse lines 62 on the collating board, and each is provided with a slot 75. Thumb screws 76, the shanks of which extend through slots 75, and the heads 77 of which are slidably mounted in the slots 73, carry resilient fingers 78 having notches 79 in their ends, the notches corresponding to the transverse lines 62 aforementioned. Thus, with this form of invention the alining strips or gages may be moved to and away from each other and the resilient clips 78 may be adjusted longitudinally of the gages and thus will serve to hold the sheets which are being collated, in position on the collating board.

In operation, assuming that the parts are in the positions illustrated in Figs. 4 and 5, the collating board is brought to a position where the sheets may be assembled by releasing the latch 23 when the collating board will, under the action of its actuating springs 15 and 19, and with or without the assistance of the operator, assume the position illustrated in Fig. 2. At this time the platen will be disposed forwardly of the typewriter carriage and the board will be in a convenient inclined position for the application of the sheets. The handles 48 are actuated so as to depress the arms 33 and consequently move the sheet shelf 35 away from the platen. The proof sheet is placed on the collating board and slipped under the angular sheet alining strips or gages 54 and the latter are permitted to drop upon the sheet by their own weight. The sheet is then fed forward until its edge lies between the platen and the sheet shelf. The proof sheet is then brought into printing position by means of the scale 64 on the sheet shelf 35, the graduations 66 on the platen, the graduations on the gages 54, or the lines 62 and 63 on the collating board. After the proof sheet is thus put in place and is properly positioned, the ledger sheets are inserted between the sheet shelf 35 and the platen and the printing position is alined in the same manner as described in connection with the proof sheets. However, the ledger sheets are placed within the sheet gages 54 and are held in position by the clips 57. The statement is inserted in much the same manner as the ledger sheets and this too is held in position by the clips 57. After all of the sheets have been properly positioned, the handles 48 are then turned to release the cams 45 and the sheet shelf will be actuated by the springs so that the rollers 41 thereon will tightly hold the sheets in place. The ledger sheets and statements are free from the clips 57 and the carbon copies are inserted between the sheets. All of the sheets and carbon papers are then turned down, by the rotation of the platen.

After the sheets have thus been positioned

the collating board is again returned to its initial position, at which time the lugs on inner carriage ends will rest in the members 31 and the inner carriage, platen, and spacing mechanism will be in its operative relation with the spacing lever 100 on the carriage. The work sheets are then turned to the desired printing position on the work sheets to the printing position on the typewriter, and the operator may thus proceed with the writing. The weight of the collating board will be distributed to the front and rear of the platen, that is to say, to the front and rear of the typewriter by the springs 15 and 19.

When the sheet alining strips or gages 54 are dispensed with, the lowermost brackets 52 may be used to assist in alining the sheets on the collating board so that the proper printing position will be obtained.

It will be noted that in the drawing the embodiment of my invention illustrated is combined with an Underwood typewriter and that only slight modifications are necessary. For instance, in order to apply the device to an Underwood typewriter, it is only necessary to remove the upper shelf, feed rollers and feed roller arms and to modify the inner carriage. The four supporting posts 2 and 4 are mounted on the outer carriage and the side bars 7 of the collating board frame are fixed to the inner carriage ends. Of course, it is to be understood that the application of the device is not confined to an Underwood typewriter, as it may be applied to any typewriter with a rotary platen.

What I claim is:

1. The combination with a rotary platen, of a collating board associated therewith, angular sheet alining strips, and means carried by the board for supporting said strips to permit their movement to and away from the board.

2. The combination with a rotary platen, of a collating board associated therewith, angular sheet alining strips, and means carried by the board for supporting said strips to permit their movement to and away from the board in acute angular relation to the board.

3. The combination with a rotary platen, of a collating board associated therewith, an angular sheet alining strip having slots therein, and supporting brackets on the board having studs extending through the slots in the strip.

4. The combination with a rotary platen, of a collating board associated therewith, an angular sheet alining strip having slots therein, and supporting brackets on the board having studs extending through the slots in the strip, said slots and board being arranged to converge toward the platen.

5. The combination with a collating board,

- 4
- of angular sheet alining strips mounted on the front thereof, and resilient clips mounted within the angles of the strips to secure the work sheets thereto.
5. 6. The combination with a collating board, of a rotary platen, feed rollers arranged to bear on the front of the platen, and means on the board supporting the feed rollers.
7. The combination with a collating board, 10 of a rotary platen, feed rollers arranged to bear on the platen, and adjustable means on the board for supporting the feed rollers.
8. The combination with a collating board, 15 of angular sheet alining strips mounted on the front thereof and movable to and away from the board, and means within the angles of the strips to secure the work sheets thereto.
9. The combination with a collating board, 20 having a pair of brackets mounted thereon, of a rotary platen, feed rollers arranged to bear on the platen, and means on the brackets for supporting the feed rollers.
10. The combination with a collating board and a rotary platen, of means for supporting the board and platen for pivotal and bodily movements, means tending to produce an upward bodily movement of the board and platen, and means carried by the board for preventing such movement, normally.
- 30 11. The combination with a typewriter, of a collating board, means located on opposite sides of the board for supporting the same on the typewriter, and means for relieving the weight of the board from the center of the carriage and for distributing the weight of the board to all of said supporting means.
12. The combination with a typewriter, of a collating board, posts on the typewriter located to the front and at the rear of the 40 board, pivoted links extending from the front posts to the lower end of the board, pivoted links extending from the rear posts to the upper end of the board, and means tending to move the board pivotally.
- 45 13. The combination with a typewriter, of a collating board, posts on the typewriter located to the front and at the rear of the board, pivoted links extending from the front posts to the lower end of the board, pivoted links extending from the rear posts to the upper end of the board, and means tending to move the board pivotally, and manually controlled means on the collating board for normally preventing such movement of the board.
- 55 14. The combination with a typewriter, of a collating board, posts on the typewriter located to the front and at the rear of the board, pivoted links extending from the front posts to the lower end of the board, pivoted links extending from the rear posts to the upper end of the board, means tending to move the board pivotally, and means for limiting the upward movement of the 60 collating board.
15. The combination with a typewriter, of a collating board, posts on the typewriter located to the front and at the rear of the board, pivoted links extending from the front posts to the lower end of the board, 70 pivoted links extending from the rear posts to the upper end of the board, means tending to move the board pivotally, and means engageable with the upper links for limiting the movement of the collating board. 75
16. The combination with a typewriter, of a collating board, posts on the typewriter located to the front and at the rear of the board, pivoted links extending from the front posts to the lower end of the board, 80 pivoted links extending from the rear posts to the upper end of the board, means tending to move the board pivotally, and adjustable means engageable with the upper links for limiting the movement of the collating board. 85
17. The combination with a typewriter, of a collating board, means for supporting the board for upward and pivotal movements, and adjustable means tending to move the board upwardly.
18. The combination with a typewriter, of a collating board, means for supporting the board for upward and pivotal movements, and springs tending to move the 95 board upwardly.
19. The combination with a typewriter, of a collating board, means for supporting the board for upward and pivotal movements, springs tending to move the board 100 upwardly, and means for varying the tension of said springs.
20. The combination with a collating board and a rotary platen associated therewith, of arms extending over said board and 105 down over the front of the platen, and means on the board for supporting the arms, said arms having feed rollers thereon arranged to bear on the front of the platen above the printing position thereon. 110
21. The combination with a typewriter carriage having a rotary platen thereon, of a collating board supported on the carriage, a paper shelf extending around the platen and to the rear of the board, a rod on the 115 carriage to support the shelf, links extending from the board to support the shelf in the rear of the board, means on the shelf to permit the latter to slide on the rod, and means on the board for moving the paper 120 shelf to permit the end of the same to project beyond the surface line of the board.
22. The combination with a typewriter, of a collating board, a movable paper shelf extending around the platen and having 125 feed rollers bearing thereagainst, links pivoted on the collating board frame and connected to the shelf for controlling the latter, and resilient means mounted on the pivot rod of the links and connected to the 130

links at a point beyond the pivot for maintaining the rollers normally in contact with the platen.

23. The combination with a typewriter, of a collating board, a movable paper shelf extending around the platen and having feed rollers bearing thereagainst, links pivoted on the collating board frame and connected to the shelf for controlling the

latter, resilient means mounted on the pivot 10 rod of the links and connected to the links at a point beyond the pivot for maintaining the rollers normally in contact with the platen, and means for varying the tension of said resilient means.

In testimony whereof I affix my signature.

JOHN A. WHERRY.
